No. 722,578.

PATENTED MAR. 10, 1903.

J. L. HAMEL.
GRAIN CAR DOOR.

APPLICATION FILED AUG. 29, 1902.

NO MODEL.

UNITED STATES PATENT OFFICE.

JOSEPH L. HAMEL, OF GRAFTON, NORTH DAKOTA.

GRAIN-CAR DOOR.

SPECIFICATION forming part of Letters Patent No. 722,578, dated March 10, 1903.

Application filed August 29, 1902. Serial No. 121,522. (No model.)

To all whom it may concern:

Be it known that I, JOSEPH L. HAMEL, a citizen of the United States, residing at Grafton, in the county of Walsh and State of North Dakota, have invented new and useful Improvements in Grain-Car Doors, of which the following is a specification.

This invention relates to a grain-car door; and the primary object thereof is to provide a simple, durable, and efficient closure for grain and other cars whereby the contents of the car may be securely retained within the same, but may be conveniently removed as occasion demands.

15 A further object is to provide a closure which will prevent leakage of grain or other like material from the interior of the car.

Other objects, as well as the peculiar construction of the invention, will be specifically 20 described hereinafter, and the novel features are clearly illustrated in the accompanying drawings, in which—

Figure 1 is a vertical longitudinal section through a car, showing my invention applied.

25 Fig. 2 is a cross-section on the line 2 2 of Fig. 1.

Referring now to the drawings by numerals of reference, 1 designates a car-body provided with suitable openings 2 and 3 in the sides thereof. Along the vertical edges of the openings 2 and 3 are wedge-shaped battens 4 and 5, the inner surfaces of which converge from the bottom toward the top of the car until they terminate on a plane approximately parallel with the sides thereof. Adjacent these 35 battens are arranged inverted-U-shaped staples 6 and 7, which form hinges for the pivoted doors 8, which are connected to the staples by means of projecting ears 9 and 10. These doors rest against the wedge-shaped 40 battens when the opening is closed, and inasmuch as the doors will be on an inclined plane—that is, at a tangent to the perpendicular—the liability of the grain working between the outer face and the side of the car 45 will be diminished.

Suspended above the doors 8 are arranged reciprocating slides 11, which are carried upon a suitable track 12 by hangers 13 and 14. The lower edge of the slide is offset at 15 50 to overlap the doors 8 and tends to hold the same in its closed position. This slide also acts as a gate to close the opening and is securely held in place by means of one or more eccentrically-pivoted latches 16, which are

secured to the side of the car at a point adjacent 55 the lower corners thereof and which are adapted to be automatically thrown in engagement therewith by a weighted handle 17. I prefer to employ two of these latches, one at each corner; but a single latch may be 60 used, if desired.

It will thus be seen that I have provided a cheap, simple, and efficient means for closing the openings in the side of the car and a closure which may be readily operated with a 65 minimum liability of getting out of order.

Having thus fully described my invention, what I claim as new, and desire to secure by Letters Patent, is—

1. In a car-door closure, the combination 70 with a car having an opening in one side thereof; of wedge-shaped battens secured to the longitudinal edges of said opening, a pivoted door adapted to be folded from the bottom of the car to rest against said battens on 75 an inclined plane, and means for locking the door with relation to the battens.

2. In a car-door closure, the combination 80 with a car having an opening in the side thereof; of battens secured to the longitudinal edges of said opening, the inner surfaces of which converge from the bottom toward the top of the car, a pivoted door secured to the bottom of the car and adapted to rest against the said battens, a sliding gate suspended above the door and adapted to overlap the same, and fastening devices adapted to engage the gate whereby the door and gate 85 will be held in a locked position.

3. In a car-door closure, the combination 90 with a car having an opening in the side thereof; of battens secured to the inner side of the car and arranged adjacent to the vertical edges of the opening, a pivoted door secured to the car and adapted to rest against 95 said battens, a sliding gate suspended above the door and adapted to overlap the upper edge thereof and gravity-actuated fastening devices adapted to engage the gate whereby the door and gate will be securely locked together to close the opening.

In testimony whereof I affix my signature in presence of two witnesses.

JOSEPH L. HAMEL.
